(57) **CLAIM**

The ornamental design for a roller stamp with knife, as shown and described.

DESCRIPTION

FIG. 1 is a front and left side perspective view of a roller stamp with knife;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is a front and left side perspective view with a cap;

FIG. 9 is a rear and right side perspective view with a cap; and,

FIG. 10 is a front elevational view thereof with the knife extended.

The broken line showings of the cap and letter cutter attachments to the roller stamp with knife is included for the purpose of illustrating environmental structure and forms no part of the claimed design.

1 Claim, 9 Drawing Sheets
